MACHINE FOR FEEDING MIXED STOCK

Application filed December 10, 1926. Serial No. 153,953.

This invention relates to a press roll machine for expressing the moisture from a substance of mixed solid and liquid character such as comminuted rubber to be re-worked and some other fibrous materials.

The principal objects of the invention are to provide means for taking the solid matters that may be dropped from the press rolls back into the feeder without the water or liquid drained therefrom in the process; to provide an improved means for operating the reciprocating plate which is employed for directly feeding the material from the inclined wall down which it slides to another machine or element, as for example a pair of press rolls, and to provide these means in the same machine without materially adding to the expense thereof.

Other objects and advantages of the invention will appear hereinafter.

Reference is to be had to the accompanying drawings in which

Fig. 1 is a side view of a press roll machine with the front wall removed to show features of this invention;

Fig. 2 is an outside view of a crank rod and means for moving it;

Fig. 3 is an enlarged sectional view of Fig. 2;

Fig. 4 is a plan of the machine; and

Fig. 5 is a side view of a modification partly in section.

The invention is shown in Figs. 1, 2, 3, and 4 as applied to a well known type of machine for extracting liquid from a mixture of materials. In this machine, a feed hopper 10 is provided having therein a feed apron 11 and the usual means for operating the same. In this case we have placed a partition 12 just below the feeding strand of the apron, or back of it, to exclude the material fed in from the space behind and another partition 13 in front of the feed apron for a similar purpose. This partition 13 is made adjustable at the top. The material fed in front of it, of course, can descend below the point where it will be picked up by the feed apron and fed upwardly in the usual way. In order to prevent too much of the stock getting down

behind the feed apron, where it is in the way and accomplishes no useful result, the partition 12 is provided and also the partition 13. The adjustment of the latter will regulate the height of material behind it.

Stock fed over the top of the apron drops on an inclined wall 14 and down to a reciprocating plate 15 at the bottom. This wall 14 is close enough to the plate to prevent material passing backwardly over the plate. The plate is reciprocated to push the material forward and over a stationary perforated plate 16 into any desired position, for example between the press rolls 17. Liquor can drain down through the perforated plate with the liquor coming down the rear side of the bottom roll 17 that is extracted by the pressure.

The plate 15 is reciprocated by cranks 18 operated by the machinery of the press in any usual way. The cranks 18 are connected with rods 19 to the plate 15. The connection is made through a compression spring 20 at the end of each crank rod which bears against a head 21 fixed on the rod and is located in a socket pivoted to the plate 15.

The normal operation is the same as usual but if a stone or any lump of foreign matter gets into the stock, the springs 20 will yield and instead of breaking the connecting rods or other pieces, the machine will continue to operate until stopped. No undue pressure is encountered at this point therefore.

The droppings from the lower press roll 17 do not consist of pure water or liquor but contain a considerable proportion of rubber and fibrous or other solid material. Under previous practice this material, which is very valuable in the mixture, is lost. For the purpose of saving it, we place below the pressure rolls 17 a means for catching the droppings and moving them back into the feed hopper where they will be picked up and fed through again. In the form shown in these figures, this means consists of an endless conveyor 25 movable in the direction indicated by the arrows in a trough having a pair of sides and an inclined bottom. About

mid-way of the bottom there is a perforated screen 27 to catch all the droppings. The conveyor consists of two chains running over sprocket wheels 28 with angle iron floats 29 riveted to the chains. On each angle iron float there is a piece of rubber 30 riveted thereto to scrape the material back into the feed hopper 10. The inclined bottom constitutes a ditch for receiving the liquor and is made up of a screen which allows the liquid 10 drainings to pass down below into an inclined trough 31 which will bring them out at one side of the machine. The more solid parts are brought into the hopper through an opening in the side and deposited under 15 the endless feed apron where they are taken back to pass through again.

In this way the finer particles of rubber, wool or other material are saved and fed through the machine again if they drop down from the extraction rolls. Furthermore, the parts that cooperate with the reciprocating plate are in no danger of being broken by the presence of iron or other hard substances in the stock.

23   Aside from the matters described herein, the machine is made in accordance with any old type of machine for this purpose. The device can be used in pushing the stock into a pair of feed rolls such as are used on pickers and openers in textile mills instead of constituting a part of a machine as described above.

Other modifications can be made and one of them is shown in Fig. 5. In this case the material is fed from the hopper 10 to the extraction rolls 17 and treated in substantially the same way as above described by a single perforated apron or conveyor. This conveyor has a strand 35 inclined upwardly for feeding the stock in the same way as the feeding apron in Fig. 1. The return strand comes downwardly and then passes out under the feed rolls to constitute a strand 36 which may extend horizontally and take the droppings from the feed rolls down to the perforated bottom 27 as in Fig. 1. The lower strand 36 takes the stock back into the hopper as described above. The discharge of the solid and liquid parts is the same as in the other form shown.

55 Although we have illustrated and described only two forms of the invention we are aware of the fact that other modifications can be made therein by any person skilled in the art without departing from the scope of the invention as expressed in the claims. Therefore, we do not wish to be limited to all the details of construction herein shown and described but what we do claim is:

1. The combination of a feed hopper with a pair of rolls in position for receiving stock therefrom, a horizontal endless conveyor located underneath the rolls to receive the

droppings therefrom, said conveyor comprising an apron having transverse floats thereon, a perforated trough located under the return lower strand of the apron in position to have the floats thereof come substantially into contact with it, the trough delivering back into the feed hopper, and a trough underneath the perforated trough and inclined in a direction for directing the liquid away from the hopper. 70 75

2. In a feeding hopper, the combination with an inclined feed apron, of a partition parallel thereto located within the hopper, and means for feeding stock backwardly into the hopper below the apron and partition. 80

In testimony whereof we have hereunto affixed our signatures.

CHAS. G. SARGENT.
